(57) **CLAIM**

I claim the ornamental design for an combination toothbrush and tongue scraper, as shown and described.

DESCRIPTION

FIG. 1 is a front perspective view of a first embodiment of a combination toothbrush and tongue scraper;

FIG. 2 is a back perspective view thereof;

FIG. 3 is a front elevation view thereof;

FIG. 4 is a back elevation view thereof;

FIG. 5 is a first side elevation view thereof;

FIG. 6 is a second side elevation view thereof;

FIG. 7 is a first end view thereof;

FIG. 8 is a second end view thereof;

FIG. 9 is a front perspective view of a second embodiment of a combination toothbrush and tongue scraper;

FIG. 10 is a back perspective view thereof;

FIG. 11 is a front elevation view thereof;

FIG. 12 is a back elevation view thereof;

FIG. 13 is a first side elevation view thereof;

FIG. 14 is a second side elevation view thereof;

FIG. 15 is a first end view thereof;

FIG. 16 is a second end view thereof;

FIG. 17 is a front perspective view of a third embodiment of a combination toothbrush and tongue scraper;

FIG. 18 is a back perspective view thereof;

FIG. 19 is a front elevation view thereof;

FIG. 20 is a back elevation view thereof;

FIG. 21 is a first side elevation view thereof;

FIG. 22 is a second side elevation view thereof;

FIG. 23 is a first end view thereof; and,

FIG. 24 is a second end view thereof.

The broken lines, where shown, are for illustrating environmental structure and form no part of the claimed design. The second embodiment is illustrated with a symbolic break in its length. The appearance of any portion of the article between the break lines forms no part of the claimed design.
